US00D764809S

(12) **United States Design Patent**
Wolfe et al.

(10) **Patent No.:** US D764,809 S
(45) **Date of Patent:** ** Aug. 30, 2016

(54) **SHEET WITH A PATTERN**

(71) Applicant: **The Procter & Gamble Company**,
Cincinnati, OH (US)

(72) Inventors: **Sarah Nicole Wolfe**, Cincinnati, OH
(US); **Ashley Marie Schwab**,
Cincinnati, OH (US); **Kimberly
Elizabeth Hawes**, Norwood, OH (US);
John Joseph Litchholt, Lawrenceburg,
IN (US); **Jason Ashley Wagner**,
Lawrenceburg, IN (US)

(73) Assignee: **The Procter & Gamble Company**,
Cincinnati, OH (US)

(**) Term: **15 Years**

(21) Appl. No.: **29/539,491**

(22) Filed: **Sep. 15, 2015**

Notice of Allowance and Examiner's Amendment for U.S. Appl. No. 29/490,961, filed May 15, 2014.

Primary Examiner — Karen S Acker
Assistant Examiner — Clare Ann Gannon

(57) **CLAIM**

The ornamental design for a sheet with a pattern, as shown and described.

DESCRIPTION

FIG. 1 illustrates a front view of a sheet with a pattern; FIG. 2 illustrates a back view of the sheet with a pattern; FIG. 3 illustrates a first end view of the sheet with a pattern; FIG. 4 illustrates a left side view of the sheet with a pattern; FIG. 5 illustrates a right side view of the sheet with a pattern; and, FIG. 6 illustrates a second end view of the sheet with a pattern. The broken lines depict environmental subject matter and form no part of the claimed design.

1 Claim, 3 Drawing Sheets
